FRAME FOR MAKING FRINGE

Cedric C. Sova, 319 S. Lake St.,
Forest Lake, Minn. 55025

Filed Oct. 19, 1972, Ser. No. 300,585

Term of patent 14 years

Int. Cl. D15—06

U.S. Cl. D92—15

FIG. 1 is a top perspective view of a frame for making fringe showing my new design;

FIG. 2 is a top plan view thereof;

FIG. 3 is an edge view taken from the left side of FIG. 1;

FIG. 4 is an edge view taken from the right side of FIG. 1;

FIG. 5 is a bottom plan view;

FIG. 6 is an end view taken in the direction of line 6—6 of FIG. 2; and

FIG. 7 is an end view taken in the direction of line 7—7 of FIG. 2.

I claim:

The ornamental design for a frame for making fringe, as shown.
